UNITED STATES PATENT OFFICE.

HERBERT T. HERR, OF PITTSBURGH, PENNSYLVANIA, ASSIGNOR, BY MESNE ASSIGNMENTS, TO THE WESTINGHOUSE MACHINE COMPANY, OF EAST PITTSBURGH, PENNSYLVANIA, A CORPORATION OF PENNSYLVANIA.

FLUID-DISTRIBUTER.

1,209,579.

Specification of Letters Patent. Patented Dec. 19, 1916.

Application filed May 1, 1913. Serial No. 764,846.

To all whom it may concern:

Be it known that I, HERBERT T. HERR, a citizen of the United States, and a resident of Pittsburgh, in the county of Allegheny and State of Pennsylvania, have made a new and useful Invention in Fluid-Distributors, of which the following is a specification.

This invention relates to means for controlling engines or the like from a distance, and particularly to a pressure distributing device, one of the objects of which is to provide means whereby a determined pressure will be exerted against a pressure actuated device affected by the distributor.

15 Another object is to provide means for controlling the distributor so that any given pressure may be maintained.

Another object is to provide a distributor having a self-contained regulating means.

20 It is also the object of the invention to provide manually controlled means for directing the distribution of the pressure to one of a plurality of conduits and for selecting the particular conduit through which

25 pressure is to be directed.

Another object of the invention is to provide means whereby fluid pressure may be exhausted from one conduit when fluid pressure is admitted to another conduit.

30 Other objects and advantages will be specifically described hereinafter, it being understood that changes in form, proportion and minor details of construction may be resorted to without departing from the spirit 35 of the invention or sacrificing any of the advantages thereof.

In the drawings: Figure 1 is a sectional view on the line 1—1 of Fig. 2 looking in the direction of the arrows; Fig. 2 is a sectional view on the line 2—2 of Fig. 1 looking in the direction of the arrows; Fig. 3 is a section on the broken line 3—3 of Fig. 1 looking in the direction of the arrows; Fig. 4 is an enlarged sectional view of the air-admitting mechanism; and, Fig. 5 is a fragmentary detail of the segment and operating handle.

Referring now to the drawings by numerals of reference: 10 indicates the casing having removable ends 11 and 12 between 50 which and the ends of the intermediate portion of the casing 10 are secured diaphragms 13 and 14; one of the ends,—in the present instance, the one designated by the reference numeral 12,—is provided with an inlet 15

adapted to be closed by a valve 16 having a 55 stem 17 and capable of being seated by a spring 19 surrounding the stem and having one end bearing against the cap 20 and the other against the valve. The valve 16 may be unseated by the diaphragm 14 and seated 60 by the spring 19. On the exhaust side of the casing and carried by the diaphragm 13 is a valve 24 adapted to close the outlet 25 of the distributor, and the diaphragms are provided with guides 26 and 27 65 which telescope one within the other. The movement of the diaphragm 14 is limited in one direction by the valve 16 and in the other direction by the flange 14^a provided with a cut-out portion 14^b to let air pass when the 70 diaphragm 14 is against it. The distributor is provided with an inlet port 29 which admits air under pressure to the interior thereof between the two diaphragms 13 and 14 into a central equalizing chamber 30. The 75 intermediate chamber is subdivided to provide an exhaust chamber 31 which under certain conditions may have communication with the chamber 30, and which exhausts to atmosphere through a suitable port, as for 80 example, the port 32, best shown in Fig. 1. The exhaust chamber 31 is shown as being approximately rectangular in cross-section (see Fig. 3). This exhaust chamber is shown as comprising a bottom 33, sides 34 and 34', 85 and a top portion 35. The top portion is provided with bearings 36 to receive a spindle or shaft 37 on which is a cam 38 adapted to turn with the shaft so as to operate a valve actuating rod 39, best shown in Figs. 90 1 and 4. The rod 39 is illustrated as comprising a tube having one end 40 closed by a plug adapted to bear against the cam 38. The tube or hollow rod 39 is provided with 95 openings 41 always registering with the inlet port 29 so that air may pass from the port 29 into the tube. The tube is normally closed at the end farthest from the point 40 by a piston valve 42, and slides in a piston 43 which is provided with openings 44 adapted to 100 register with openings 45 in the tube. The valve 42 for the tube 39 is adapted to cover a central port 46 in the piston through which air may exhaust and pass out through the ports 47 to a conduit 48 to the exhaust chamber 31. The valve 42 in the tube 39 is provided with a pin or projection 49 around 105 which is a coil spring 50, one end of which

bears against the valve 42 and the other against a spring seat 51 in the piston 43. One end of the piston 43 is to be provided with a point bearing 52 which seats against 5 a spring pressed seat 53. One end of a coil spring 54 abuts against seat 53 and one end bears against a screw plug 55 in the main casing, the screw plug 55 being adapted to be used as an adjustment for varying the 10 tension of the spring 54.

By reference to Figs. 1, 2, and 3 it will be observed that the inlet and exhaust chambers formed by the intermediate section 10 and the ends 11 and 12 are connected by a 15 passage 56 which permits the two end chambers to be in communication with the air chest 57 through the medium of the said passage 56 and a passage 58, there being a distributing valve 59 in the air chest, as best shown in Figs. 1 and 3. In addition to the port 58 there is a port 60 which leads from the air chest to a suitable conduit (not shown) which may be connected to an element to be actuated by fluid pressure, as for 20 example, to the ahead stage valve of a turbine. There is also a port 61 through which air may exhaust from the air chest to a suitable element to be actuated, as for example, to an astern stage valve of a turbine, it being understood, of course, that these conduits may connect to some valve actuating mechanism, as for example, a relay or valve 25 motor.

The valve 59 is in the form of a D-valve 30 and is caused to bear upon its seat 62 by a spring 63 which bears against said valve. The valve is shown as being connected to a stem 64 loose on the shaft 37 which carries the cam 38 so that when the rod or shaft 37 35 is rotated by the handle 68 the stem 64 will not be disturbed, so that when the handle 68 is moved to rotate the shaft 37, or partially rotate it, the cam 38 will actuate the rod 39 but will leave the valve undisturbed, the 40 valve being actuated only by a longitudinal motion of the shaft 38. The supply chamber 12' is connected to a suitable source of supply through the port 69 by a connecting passage 70 (see Fig. 2), and the exhaust passage 71 for the chamber 11' is connected 45 to the exhaust chamber 31 through a connecting passage 72.

The shaft 37 is rotatable in a bush 73 which supports a segment 74 carrying selective slots, in one of which will move the handle 68 when one fluid actuating element is to be operated, as for example the ahead stage valve mechanism, and in the other of which the handle will move when another 50 fluid actuated device is to be controlled, as for example, the astern stage valve mechanism of a turbine; one of the slots is designated by the reference numeral 75 and the other by the reference numeral 76 (see Fig. 55). It will be observed that these two slots

are out of alignment so that when the ahead stage valve mechanism is to be operated by air pressure, the handle 68 will be moved toward the casing so as to cause the valve 59 to shut off communication between the 70 port 58 and the port 61, and open communication between the port 58 and the port 60. In this position air will flow from the port 58 to the port 60 to the ahead stage valve mechanism, but should it be desired to operate the astern stage valve mechanism, the handle 68 will be moved into the slot 76 so as to shift the valve 59, closing communication between the port 58 and the port 60 and opening communication between the 75 port 58 and the port 61 so that air will flow only to the astern stage valve mechanism. When one of the ports 60 or 61 is in communication with the port 58, the other will be exhausting as indicated by the arrows in 80 Fig. 1. The exhausted air will pass directly into the exhaust chamber 31 and pass off to atmosphere through the port 32.

The amount of pressure which is supplied to either of the valve actuating mechanisms will be determined by the position of the handle on the segment 74 for which purpose the segment may be graduated or calibrated for difference of pressure from zero to the maximum pressure within the 90 pressure supplying medium. For example, if the handle 68 is moved to a point on the segment corresponding to 10 pounds pressure, the shaft 37 will be rotated in the bearing 36 so as to cause the cam 38 to move 100 the hollow rod or tube 39 in a direction indicated by the arrow so as cause the end 42, which is really a valve, to open communication between the tube and a port 79 which communicates with the central chamber 30 105 until 10 pounds pressure exists in the central chamber 30, in which event the pressure against the end 43' of the piston 43 will move the piston against action of the spring 54 so as to close communication between the central chamber and the source of 110 supply due to the fact that the valve 42 is lapped; and while the interior of the tube 39 is always in communication with the port 29 through the openings 41 air can get into 115 the central chamber only when the ports 44 are uncovered by the valve 42. Suppose the handle is set for 10 pounds pressure, when a pressure of 10 pounds occurs in the chamber 30 the pressure exerted against the dia- 120 phragm 14 will unseat the valve 16 and cause air under pressure to pass from the supply port 29 through port 70 through port 69, pass the unseated valve into the chamber 12' through the passage 56 over 125 to the exhaust side 11' of the casing into the air chest 57, from which it may be distributed to the air actuated device to be controlled. When the pressure in the chamber 12' is equal to 10 pounds, the pressures on 130

opposite sides of the diaphragms 13 and 14 will be equalized and the valve 16 will be closed by the spring 19 so that 10 pounds pressure will be maintained in the distributing system. Of course, there may be some little leak in the line, in which event the pressure in the end chambers will drop slightly causing the preponderating pressure in the central chamber to again open 10 the valve 16 to maintain the pressure approximately constant in the source of distribution. If it is desired to add 20 pounds or any pressure in excess of that then existing in the system, the handle will be operated to cause the shaft 37 to be rotated further so as to further unseat the valve 42 to admit more pressure to the central chamber. Suppose, however, it is desired to decrease the pressure: The handle will be reversed so as to turn the cam 38 and under the action of the spring 50 against the valve 42 communication will be established between the central chamber and the passage 46 while communication is shut off between 15 the central chamber and the interior of the tube 39. Air will then exhaust from the central chamber through the central passage in the piston out through the ports 47 around the spring seat 53, through passage 30 48 to the exhaust chamber 31 and out to atmosphere through port 32. This is best shown in Figs. 1 and 4. If there is 30 pounds pressure existing in the central chamber and the handle is moved to a suitable point to indicate that 15 pounds pressure is to be exhausted, the cam will be rotated so as to permit the hollow rod or tube to move under the action of the spring 35 a sufficient distance to unlap the exhaust 40 port so that 15 pounds pressure may exhaust, at which time the piston under the action of the spring 54 will close off communication between the exhaust and the central chamber, and 15 pounds pressure will 45 be maintained in the central chamber. The reduction of pressure in the central chamber will essentially cause a reduction of pressure in the line, for if 15 pounds pressure is exhausted from the central chamber there 50 will be a preponderance of 15 pounds pressure on the outer sides of the diaphragms. The preponderance of pressure will therefore cause the diaphragm 13 to move toward the diaphragm 14 so as to unseat the exhaust 55 valve 24 and permit air to exhaust into the passage 71 and out through the exhaust until an equilibrium of pressure is established between the central chamber and the two end chambers, at which time 60 the pressure in the system will be maintained at 15 pounds. It will be apparent that with all the parts in proper working order it will only be necessary to rotate the shaft 37 so as to cause the cam to control 65 the position of the tube 39 to maintain any pressure in the system, and that a slight reciprocation of the shaft 37 due to the particular slot in which handle 68 happens to be will determine into which port, that is, 60 or 61, the air is to be distributed. 70 Having thus described my invention, what I claim is:

1. In a pressure distributing device, a casing having a central chamber and two end chambers, flexible walls separating the end chambers from the central chamber, means for admitting pressure to the two end chambers and connected to one of the flexible walls, means for exhausting pressure from the end chambers and connected to one of the flexible walls, and means within the casing for controlling the delivery of air pressure to the central chamber. 75

2. In a pressure distributing device, a casing having a central chamber and two end chambers, said chambers being separated by flexible walls, port closing valves connected to said flexible walls 80 connected to said flexible walls and means for admitting pressure to said central chamber, said means being contained within the casing and having a sliding port closing valve. 85

3. In a device of the class described, a casing having a central chamber and two end chambers separated by flexible walls, port closing valves connected to said flexible walls 90 for admitting and exhausting pressure to and from said end chambers, a plurality of ports in communication with the end chambers, means for valving said ports, means for admitting a determined air pressure to the central chamber, and a manually controlled means connected to the air admission means for the central chamber and to the means for valving the said ports so as to 95 direct the air from the end chambers to a determined port. 100

4. An apparatus for controlling the delivery of fluid under pressure to a fluid actuated mechanism, comprising a chamber 110 from which pressure is delivered to the mechanism, pressure responsive means for controlling the degree of pressure within the chamber, a manually adjustable pressure control valve for controlling the delivery 115 of actuating pressure to said pressure responsive means, and a device, movable in response to variations of pressure to which said pressure responsive means are subjected, for controlling the delivery of fluid past said 120 valve. 125

5. An apparatus for controlling the delivery of fluid under pressure to a fluid actuated mechanism, comprising a pressure chamber from which fluid is delivered, a control mechanism for controlling the amount of pressure in said chamber, a valve 125 for controlling the delivery of pressure to said control mechanism, and pressure responsive means cooperating with said valve 130

for maintaining different determined fluid pressures on said control mechanism for each position of said valve.

6. An apparatus for controlling the delivery of fluid under pressure to a fluid actuated mechanism, comprising a pressure chamber from which fluid is delivered to said mechanism, diaphragm actuated valves for controlling the delivery of pressure to and the discharge of pressure from said chamber, a valve for controlling the delivery of actuating pressure to said diaphragms, and means responsive to pressure admitted to said diaphragms for maintaining a different determined pressure on the diaphragms for each position of said valve.

7. An apparatus for controlling the supply of fluid under pressure, comprising a pressure delivery chamber in open communication with a delivery passage, in combination with a source of pressure supply, an inlet valve between said source of supply and said chamber for delivering fluid under pressure to said chamber, a discharge valve for discharging pressure from said chamber, independent pressure responsive means for separately controlling the operation of said valves, a manually controlled valve for delivering the controlling pressure to said pressure responsive means, and a pressure responsive device for limiting the pressure delivered by said valve to said pressure responsive means.

8. An apparatus for controlling the supply of fluid under pressure, comprising a pressure delivery chamber in open communication with a pressure supply passage, in combination with a source of fluid supply, independent valves for controlling the delivery of fluid from said source to said chamber, and the discharge of fluid from said chamber, independent pressure responsive means for controlling the operation of each of said valves, a pressure chamber for sub-jecting said pressure responsive means to operating pressure, a manually controlled valve for controlling the delivery of pres-

sure to, and the discharge of pressure from said pressure chamber, and means subjected to the pressure within the chamber and co-operating with said valve for limiting the pressure variation within the pressure chamber.

9. An apparatus for controlling the delivery of fluid under pressure, comprising a pressure delivery chamber in open communication with a pressure supply passage, independent spring pressed valves for controlling the delivery of fluid to, and the discharge of fluid from said chamber, separate pressure responsive means for controlling the operation of each valve, a manually operated valve for controlling the delivery of pressure to said pressure responsive means, and a pressure responsive device for limiting the pressure to which said pressure responsive means is subjected to a definite pressure for each position of the valve.

10. An apparatus for controlling the delivery of fluid under pressure, comprising a pressure delivery chamber in open communication with a pressure supply passage, in combination with a source of fluid pressure, separate valves for controlling the delivery of fluid pressure from said source to said chamber and the discharge of fluid to the atmosphere from said chamber, a separate pressure actuated valve operating diaphragm for each valve, a chamber for subjecting said diaphragms to actuating pressure, a valve for admitting pressure from said source to said pressure chamber, automatic means for limiting the pressure within said pressure chamber to a definite pressure for each position of the valve, and a spring located between each valve and its operating dia-phragm for holding the valve on its seat.

In testimony whereof, I have hereunto subscribed my name this 23rd day of April, 1913.

HERBERT T. HERR.
